UNITED STATES PATENT OFFICE

ELBERT C. ALDRICH, OF GRANBY, MASSACHUSETTS

DESIGN FOR A DOOR KNOCKER

Application filed January 10, 1930. Serial No. 34,092. Term of patent 14 years.

To all whom it may concern:

Be it known that I, ELBERT C. ALDRICH, a citizen of the United States of America, residing at Granby, in the county of Hampshire and State of Massachusetts, have invented a new, original, and ornamental Design for Door Knockers, of which the following is a specification, reference being had to the accompanying drawing, forming a part thereof.

Fig. 1 is a front elevational view of a door knocker showing my new design; and
Fig. 2 is a side elevational view of the same.

I claim:

The ornamental design for a door knocker, as shown.

ELBERT C. ALDRICH.
